UNITED STATES PATENT OFFICE.

WILLIAM GOYNE, OF ASHLAND, PENNSYLVANIA.

ROPE SHEAVE OR PULLEY.

SPECIFICATION forming part of Letters Patent No. 459,577, dated September 15, 1891.

Application filed June 10, 1891. Serial No. 395,745. (No model.)

To all whom it may concern:

Be it known that I, WILLIAM GOYNE, a citizen of the United States, and a resident of 5
Ashland, Schuylkill county, Pennsylvania,
have invented certain Improvements in Rope
Sheaves or Pulleys, of which the following is
a specification.

The object of my invention is to so secure
a wooden lining within the groove of a metal
sheave or pulley for wire ropes that, while
said lining is effectually retained, it can be
readily applied or can be renewed without
necessitating the taking down of the sheave,
or even the unshipping of the rope, the sheave,
15 moreover, being, if desired, formed in one
piece, so that no bolts or other confining de-
vices are required, as in the case of ordinary
two-part sheaves having the lining-blocks con-
fined between said parts.

20 In the accompanying drawings, Figure 1 is
a transverse section of a rope sheave or pul-
ley having a lining applied thereto in ac-
cordance with my invention; and Fig. 2 is a
section on the line 1 2, Fig. 1.

25 The sheave or pulley A is cast or otherwise
formed with a groove for the reception of the
lining-blocks B, this groove being as to its
outer portion flared outwardly, as usual, and
as to its inner portion being, by preference,
30 also flared outwardly, so as to be undercut, as
shown in Fig. 1. Each of the lining-blocks
B has an outer flaring portion substantially
like that of the outer flaring portion of the
groove of the sheave, the inner portion of
35 each block being of such width that it will
pass freely through the contracted portion of
the groove, as shown in Fig. 1, and this in-
ner portion of each block being preferably
recessed at each side, so as to form a dove-
40 tailed or undercut tongue a at the base of
each block. The blocks are secured in place
in the groove of the sheave by means of cem-
ment of such a character that it can be intro-
duced while in a fluid state, so as to com-
45 pletely fill all the interstices or spaces be-
tween the sides of the blocks and the walls
of the groove. Hence when the cement cools
or hardens the blocks will be rigidly secured
in place in the groove. The cement which I
50 prefer to use for the purpose is sulphur, which
can be readily melted and poured and is not
subject to expansion and contraction by any

variations in temperature to which the sheave
may be subjected; nor is it so affected by moist-
ure as to cause it to lose its hold upon the 55
blocks. The blocks may be held in position
on the pulley by any suitable means while
the cement is being poured in the groove, one
of the blocks being removed for this purpose
or a suitable opening being formed in one of 60
the blocks through which to pour the cement.
The sheave can be readily relined when the
original lining becomes worn, this operation
being effected without removing the sheave
from its bearings, or even, if desired, with- 65
out unshipping the rope, by cutting out the
worn blocks from that portion of the pulley
which is not covered by the rope, inserting
new blocks in their places, cementing these
blocks in position, and then turning the pul- 70
ley, so that the blocks which were before cov-
ered by the rope are rendered accessible and
can be removed in the same way and new
blocks substituted therefor.

75 While the undercutting of both the groove
and the lining-blocks is preferred, it is not ab-
solutely essential to the main feature of my
invention, as the inner portions of the walls
of the groove, and also of the blocks, may be
straight, if desired, the hold of the cement 80
upon the sides of the blocks and upon the
walls of the groove being relied upon to pre-
vent any displacement of the blocks.

85 My invention effectually overcomes certain
objections to the two-part sheaves now ordi-
narily employed, in which the lining-blocks
are confined between the two parts of the
sheave, the latter being secured together by
transverse bolts. In sheaves of this class the
lining-blocks must be very accurately made, 90
in order that the flanges of the sheave will
have an equal bearing upon all of the blocks,
for if some of the blocks are slightly larger
than the others the flanges will bind upon
these blocks and the remaining blocks will 95
be loose. The use of the bolts and nuts for
securing the parts of such a sheave together
is also objectionable, both on account of in-
convenience and expense and because if the
bolts pass through the blocks the wearing 100
away of the latter will expose the bolts and
cause the same to wear the rope.

Having thus described my invention, I
claim and desire to secure by Letters Patent—

1. A rope sheave or pulley having a grooved rim with lining-blocks having their inner portions of less width than the narrowest portion of the groove, so that they are capable of being fitted radially into said groove, said blocks being secured therein by cement filling the spaces between the blocks and the walls of the groove, substantially as specified.
2. A rope sheave or pulley having a grooved rim and lining-blocks having their inner portions of less width than the narrowest portion of the groove, so that they are capable of being fitted radially into said groove, said blocks being secured therein by cement filling the spaces between the blocks and the walls of the groove, one or other of said parts being undercut as to its inner portion, substantially as specified.
3. A rope sheave or pulley having a grooved rim and lining-blocks having their inner portions of less width than the narrowest portion of the groove, so that they are capable of being fitted radially into said groove, said blocks being secured therein by cement filling the spaces between the blocks and the walls of the groove, both the blocks and walls of the groove being undercut as to their inner portions, substantially as specified.

In testimony whereof I have signed my name to this specification in the presence of two subscribing witnesses.

WILLIAM GOYNE.
